TIMING DEVICE

Phillip S. Edmunds, Troy, Ohio

Application July 6, 1935, Serial No. 30,145

5 Claims. (Cl. 161—26)

This invention relates to timing devices and more particularly to a device for operating or initiating the operation of any desired mechanism after a predetermined length of time. The invention has particular utility in releasing a toy parachute or other device from a toy airplane because of its extreme simplicity and the lightness of the materials from which it can be fabricated, but its utility is not limited thereto.

10 One object of the invention is to provide a simple and light weight timing device.

Another object is to provide a timing device capable of operating or initiating the operation of any desired mechanism after a predetermined time delay.

15 A further object of the invention resides in the provision of a device for releasing a toy parachute or other device from a toy airplane at a predetermined time after the release of said airplane.

20 A still further object is to provide a device for operating the shutter of a photographic camera or similar device after a predetermined time delay.

25 Other objects and advantages of the invention will appear in the following detail description of the preferred embodiments of the invention illustrated in the attached drawing of which:

Fig. 1 illustrates a device according to the 30 present invention as applied to a toy airplane;

Fig. 2 is a sectional view taken on the lines 2—2 of Fig. 1; and

Fig. 3 is an elevation of a modification of the 35 invention as applied to a camera.

Referring more particularly to the drawing, the device illustrated in Figs. 1 and 2 includes a base plate 10, a pivoted member 11, a friction element 12, and a spring 13. The pivoted member 11 is pivotally mounted upon the base plate 10 at 14 and is provided with a friction element 40 engaging arm 15, a latching arm 16 and an actuating arm 17. The pivoted member 11 is resiliently urged in a clockwise direction in Fig. 1 by the spring 13 attached to a lug 18 upon the base plate 10 and engaging a lug 19 carried by the friction element engaging arm 15 of the pivoted member. The clockwise movement of the pivoted member is limited by a stop 20 carried by the base plate. The arm 15 of the pivoted member terminates in an upturned portion 21, the outer surface of which is concentric with the pivot 14. The upturned portion 21 is adapted to frictionally engage the friction element 12 which is secured to a plate 22 provided with slots 23 so 50 as to be adjustably attached to the base plate 10.

by screws 24. The friction element has an inner arcuate surface also concentric with the pivot 14 and is adjusted to provide substantially uniform pressure against the upturned portion 21 of the pivoted member in all contacting positions thereof with the friction element. The friction element is preferably formed of a resilient friction material such as vulcanized rubber although any friction material which will provide for uniform retarded movement of the pivoted member may 5 be employed. The latching arm 16 is adapted to be positioned below hinged flaps or doors 25 in the lower surface of a toy airplane so as to maintain the doors in closed position in the full line position of the pivoted member.

15 In operating the device of Figs. 1 and 2, a toy parachute, bomb, or other object is placed in a cavity in the airplane above the doors 25, the doors closed and the pivoted member manually rotated by the actuating arm 17 into the full line position of Fig. 1. The actuating arm 17 is released at the same time the toy airplane is released and the pivoted member slowly rotates in a clockwise direction in Fig. 1 under the influence of spring 13. This rotation is retarded by the friction element 12 until the friction engaging portion 21 approaches the end of friction element 12 at which time the pivoted member suddenly snaps into the dotted line position of Fig. 1 to release the doors 25. The time delay before 20 releasing the doors 25 can be varied by varying the starting position of the pivoted member relative to the friction element 12.

25 The modification of the device shown in Fig. 3 is generally similar to that shown in Figs. 1 and 2, and is adapted to control the exposure time of 30 a camera and includes a base plate 10' adapted to be secured to a camera with an aperture 26 in the base plate positioned in front of the camera lens 27. A pivoted member 11' is pivoted to 35 the base plate 10' at 14' and is provided with an actuating arm 17', shutter arms 15' and 16' separated by an exposure gap 28 and a friction element engaging portion 21'. A spring 13' is secured to the base plate 10' at 18' and urges the 40 pivoted member in a clockwise direction in Fig. 3 by engagement with a lug 19' carried by the pivoted member. The base plate 10' carries a friction element 12' secured thereto and a stop 45 20' to limit the movement of the pivoted member.

50 In operation, the pivoted member 11' of the device of Fig. 3 is rotated in a counterclockwise direction by the actuating arm 17' until the lens 27 is covered by the shutter arm 15' and the fric- 55

tion engaging portion 21' is near the left end of the friction element 12'. The actuating arm is then released and the pivoted member is moved by the spring 13' slowly in a clockwise direction 5 keeping the lens covered until the friction engaging portion 21' approaches the right end of the friction element at which time the pivoted member snaps to a position against the stop 20'. During this rapid movement the lens 27 is exposed for a short period of time through the gap 28 and is then covered by the shutter arm 16'.

The modification of Fig. 3 may be used for making pictures of the operator of the camera, who may adjust the pivoted member and then join 15 the group upon which the camera has been focused before the exposure is completed. Also because of the light weight of the materials from which the device may be constructed, it is particularly adapted for attachment to cameras attached to kites, balloons or model airplanes. The 20 rigid portions of both the modifications herein disclosed are preferably made of relatively thin sheet aluminum and the springs are preferably light strips of spring metal or piano wire. The 25 friction elements may be light strips of soft lively rubber. The friction elements may be of any length desired in order to provide for different periods of time delay. Also the time delay may be controlled within limits by varying the pressure 30 between the friction element and engaging portion of the pivoted member, for example, by adjusting the friction element toward or away from the central pivot. By providing arcuate friction elements concentric with the pivot, substantially 35 uniform pressure is obtained and a slow regular movement of the movable member produced.

While I have described the preferred embodiments of my invention it is understood that the 40 invention is not to be limited to the exact details or uses of the invention disclosed but may be varied within the scope of the following claims.

I claim as my invention

1. A timing device comprising a base, a movable member, a pivot connecting said member to said base for pivotal movement of said member, resilient means for moving said member in one direction, and a resilient friction element secured to said base and having a friction surface forming a segment of a cylinder concentric with said pivot, said member having a portion contacting said surface and being rigid between said pivot and said portion so as to have its movement substantially uniformly retarded by said friction surface.

2. A timing device comprising a base, a movable member, a pivot connecting said member to said base for pivotal movement of said member, resilient means for moving said member in one direction, and a soft rubber friction element adjustably secured to said base and having a friction surface forming a segment of a cylinder concentric with said pivot, said member having a

portion contacting said surface and being rigid between said pivot and said portion so as to have its movement substantially uniformly retarded by said friction surface.

3. A timing device comprising a base, a movable member, a pivot connecting said member to said base for pivotal movement of said member, resilient means for moving said member in one direction, a resilient friction element secured to said base and having a friction surface forming a segment of a cylinder concentric with said pivot, said member having a portion contacting said surface during a portion only of its movement and being rigid between said pivot and said portion so as to have its movement substantially uniformly retarded by said friction surface and a stop for limiting the movement of said member after said portion moves out of engagement with said surface.

4. In a timing device for releasing after a time delay an article such as a parachute from a model airplane having a cavity for said article and a closure for said cavity, the combination of a base, a movable member for securing said closure in closed position, a pivot connecting said member to said base for pivotal movement, resilient means for moving said member in a direction to release said closure, and a resilient friction element secured to said base and having a friction surface forming a segment of a cylinder concentric with said pivot, said member having a portion contacting said surface and being rigid between said pivot and said portion so as to have its movement substantially uniformly retarded by said friction surface, said member securing said closure in closed position for at least a portion of said retarded movement and then releasing said closure.

5. In a timing device for effecting an exposure after a time delay of a photographic camera having an aperture, the combination of a base, a movable member having a pair of spaced light intercepting means adapted to be successively positioned before said aperture, a pivot connecting said member to said base for pivotal movement, resilient means for moving said member in a direction to successively position said elements before said aperture, and a resilient friction element secured to said base and having a friction surface forming a segment of a cylinder concentric with said pivot, said member having a portion contacting said surface during a part only of its movement and being rigid between said pivot and said portion so as to provide for substantially uniformly retarded movement during a part of its movement and rapid movement during the remainder of said movement, one of said light intercepting means being positioned before said aperture during said retarded movement and the other of said light intercepting means being positioned before said aperture after said rapid movement.

PHILLIP S. EDMUND.
